UNITED STATES PATENT OFFICE.

VICTOR GEORGE WILLIAM GILBERT, OF LONDON, ENGLAND, AND FRANK H. STEINICKE, OF NEW YORK, N. Y., ASSIGNEES TO FOAMITE-CHILDS CORPORATION, OF NEW YORK, N. Y., A CORPORATION OF DELAWARE.

MARINE FIRE-EXTINGUISHING SYSTEM.

Application filed September 15, 1921. Serial No. 500,964.

The invention relates to fire extinguishing apparatus, in which normally separated chemical solutions are mixed in time of fire to produce a fire-extinguishing foam and has 5 special reference to the construction and design of the devices for mixing the solutions and distributing the foam over a wide area, being particularly adapted for use in foam systems for the protection of oil fired ships 10 and the like. In such systems a number of foam delivery units is required to be distributively located over the tank top of the ship, which represents a considerable area, having very limited head room or space 15 above it. The function of the units is to cover or coat the entire area substantially uniformly with a blanket of foam in time of fire, and in the interest of economy it is desirable that each unit be effective over an 20 area of large radius. This result has been found to be practically possible of accomplishment, with the production and delivery of foam of good quality, by means of the device herein disclosed, which is in the nature 25 of a pipe fixture and combines, in one structure, a mixing chamber and a delivery chamber the latter having relatively restricted foam projecting outlets.

Fig. 1 is a plan view of a foam distributing system embodying the present invention, the arrangement shown being particularly suitable for ship tank tops or other risk areas having limited headroom;

Fig. 2 is a larger scale view of one of the distributor fittings or heads; and

Figs. 3, 4 and 5 are detail views of the same.

In the installation shown in Fig. 1 the area to be protected is divided into three 40 zones, each provided with its own solution supply lines designated 45, 46, 45', 46', 45'', 46'' respectively, this arrangement being convenient and highly efficient, although obviously not essential, and since the connections are similar for each zone reference 45 will be made to but one of them, the corresponding indexed numerals indicating the corresponding parts in the other zones.

The solution lines 45, 46 which carry the 50 component foam making solutions from the source of supply (not shown) are connected with a plurality of branch lines 47, 48, each of which is in turn connected to a number of suitably located distributors or heads

49, each as shown in Fig. 2, comprising an 55 elongated chamber, having oppositely closed ends 72 and a plurality of distributively-spaced jet openings 77. The connection of the branch lines 47 and 48 to the various heads 49 is preferably by way of a number 60 of sub-branches or manifolds, 73, 74, which communicate with the heads at spaced intervals throughout their length. It is also desirable, as shown in Fig. 3, that these sub-branches enter the heads in opposed relationship whereby the intermixture of the solutions is commenced as soon as they enter 65 the distributors:

As shown in Figs 4 and 5 (which are 70 sections on the lines X-X and Y-Y of Fig. 2) the jet openings may be variously distributed throughout the length of the heads, their arrangement being such as to ensure a complete blanketing of the risk area in which each head is located assisted by the 75 provision of a sufficient number of sub-branches 73, 74 to substantially sub-divide each head 49 into a number of supply and discharge sections of short length.

Referring to Fig. 1 again, it will be seen 80 that the heads or distributors 50 which protect the narrow area at the end of the system are connected directly, and at their centers only, with the branch lines 47, 48, their construction otherwise however is as described above.

It will thus be apparent that we have 85 provided an improved foam fire extinguishing system by which the foam can be distributed to a great lateral distance with uniformity of application and a system which is particularly suited for marine use or the 90 protection of other places in which the construction of the necessary apparatus is subject to similar limitations as to size and 95 form. The structure disclosed is, however, subject to modification to suit the conditions at hand without departing from the scope of the following claims.

We claim:

1. In apparatus of the class described, the combination with a plurality of means to supply solutions forming fire extinguishing foam when mixed, and means to distribute the foam over a wide area, including mixing chambers having materially great length in proportion to cross section, each with a plurality of connections for each solution sup-

plying means arranged at spaced intervals in opposed relationship throughout the length of the chamber, and a multitude of discharge openings.

5. In apparatus of the class described, a mixing chamber relatively long in proportion to its cross section, and provided with opposed sets of solution supplying inlets, and with discharge openings throughout its length, the inlets of the sets at spaced intervals.

6. In apparatus of the class described, a mixing chamber relatively long in proportion to cross section, and having opposed sets of solution supplying inlets, and perforate and imperforate portions, the imperforate portions at the top of the chamber, and the inlets of the sets at spaced intervals.

7. An apparatus for extinguishing fires in the region beneath the boiler room floor of an oil burning ship comprising a plurality of mixing chambers distributed in the space between the boiler room floor and the inner bottom or tank top of the ship, means for conducting to said mixing chambers in time of fire chemical component solutions for

comixture to produce a fire extinguishing foam compound, each chamber relatively long in proportion to cross section, provided with perforate portions, and having a plurality of pairs of opposed inlets for the several solutions.

8. A distributor fitting for foam-type fire extinguishing systems adapted for uniformly distributing foam in places having limited headroom, comprising a mixing chamber, relatively long in proportion to its cross section and provided with a plurality of individual, distributively-spaced jet orifices; and a plurality of manifolds each provided with an inlet connection and communicating with said mixing chamber at a plurality of spaced points throughout its length.

Signed by the said VICTOR G. W. GILBERT at London, England, this 1st day of September, A. D. 1921.

VICTOR GEORGE WILLIAM GILBERT.
